(57) **CLAIM**

The ornamental design for a one-way keyed and ratcheted tensioning device with side release action, as shown herein.

DESCRIPTION

FIG. 1 is a perspective view of the invention; the broken line showing of the strap is included for the purpose of illustrating and forms no part of the claimed design;

FIG. 2 is a perspective view of the invention;
FIG. 3 is an exploded view of the invention;
FIG. 4 is a perspective view of the key portion of the invention, shown separately for clarity of illustration;
FIG. 5 is a front view of the key of FIG. 4;
FIG. 6 is a left side view of the key of FIG. 4;
FIG. 7 is a top view of the key of FIG. 4;
FIG. 8 is a back view of the key of FIG. 4;
FIG. 9 is a bottom view of the key of FIG. 4;
FIG. 10 is a right side view of the key of FIG. 4;
FIG. 11 is a perspective view of the ratcheted portion of the invention, shown separately for clarity of illustration;
FIG. 12 is a side view of the ratcheted portion of FIG. 11;
FIG. 13 is a side view of the ratcheted portion of FIG. 11;
FIG. 14 is a top view of the ratcheted portion of FIG. 11;
FIG. 15 is a bottom view of the ratcheted portion of FIG. 11;
FIG. 16 is a side view of the ratcheted portion of FIG. 11;
FIG. 17 is a side view of the ratcheted portion of FIG. 11;
FIG. 18 is a perspective view of the frame portion of the invention, shown separately for clarity of illustration;
FIG. 19 is an end view of the frame portion of FIG. 18;
FIG. 20 is an opposite end view of the frame portion FIG. 18;
FIG. 21 is a top view of the frame portion of FIG. 18;
FIG. 22 is a bottom view of the frame portion of FIG. 18;
FIG. 23 is a front view of the frame portion of FIG. 18;
FIG. 24 is a rear view of the frame portion of FIG. 18;
FIG. 25 is a perspective view of the locking ring of the invention, shown separately for clarity of illustration;
FIG. 26 is a top view of the locking ring of FIG. 25;
FIG. 27 is a bottom view of the locking ring of FIG. 25;
FIG. 28 is a side view of the locking ring of FIG. 25;
FIG. 29 is a side view of the locking ring of FIG. 25;
FIG. 30 is a side view of the locking ring of FIG. 25; and
FIG. 31 is a side view of the locking ring of FIG. 25.
